WILLIAM GORMAN.

United States Patent Office.

WILLIAM GORMAN, OF NEW BRITAIN, CONNECTICUT, ASSIGNOR TO THE RUSSELL AND ERWIN MANUFACTURING COMPANY, OF SAME PLACE.

Design No. 3,607, dated August 10, 1869.

DESIGN FOR A DOOR-ESCUTCHEON.

The Schedule referred to in these Letters Patent and making part of the same.

all whom it may concern:

Be it known that I, WILLIAM GORMAN, of New Britain, in the county of Hartford, and State of Connecticut, have originated and designed a new Design Door-Escutcheon; and I do hereby declare that the following is a full, clear, and exact description thereof, reference being had to the accompanying drawings, being a part of this specification.

The outer edge of the escutcheon is surrounded by raised moulding. This moulding is composed of two members. The outer one, *a*, is plain, and the inner one, *b*, is embossed. Both are raised above the matted ground *A*, but in different degrees, as shown.

The effect sought to be produced is that of a sunken panel relieved by an edge moulding. The key-hole guard is of corresponding design, and the large spaces of the ground are filled with ornamental scroll-work, as shown.

What I claim as my invention, and desire to secure by Letters Patent, is—

The new ornamental design for a door-escutcheon, substantially as described, and shown in the drawings.

WILLIAM GORMAN.
